HIGH SPEED CONTAINER FILLING MACHINE

John R. Naibach, Oak Park, Ill., assignor to John R. Naibach Engineering Co., Chicago, Ill., a corporation of Illinois

Application March 16, 1956, Serial No. 572,057

12 Claims. (Cl. 141—148)

The present invention relates to machines for filling a continuously moving parade of upwardly open cans or containers with a pulverous or particled material by telescoping the successive cans around individual vertical filling tubes which rotate together in an annular assembly that measures the material through the tubes into the respective cans.

One object of the invention is to provide unique improvements and sharp increases in the operating capabilities of a filling machine of the above character without increasing the size of the machine.

More specifically stated, another object of the invention is to provide an improved filling machine which, as compared to conventional machines of similar size, has an output capacity that is distinctly increased in regard to both the maximum numerical rate at which containers can be filled and the maximum quantity of material that can be accurately measured into individual containers filled at any given numerical rate.

A related object is to provide an improved filling machine, as recited, which is capable of accurately filling tall cans as well as short cans with substantially the same extraordinary efficiency—the machine being readily adjustable to accommodate cans of different height.

A further object is to provide an improved filling machine of the above character in which a large portion of the circumferential movement of each filling tube previously consumed in telescoping a container into filling position relative to the tube is utilized to lengthen the arcuate path through which the tube is operative to measure out the material for filling the container, thus increasing the operating efficiency and capacity of the machine.

Another object is to provide an improved machine as characterized above, in which troublesome jamming by fouled cans is avoided by the action of novel can elevating means in the machine that responds automatically to any abnormal resistance to movement of the cans into telescoping relation to the filling tubes. A related object is to provide for quick replacement in the machine of any can which fails to move normally into telescoping relation to its filling tube.

Another object is to provide in a filling machine for telescoping even imperfect cans around filling tubes with extraordinary certainty and dependability, using for this purpose improved telescoping means which inherently has an unusually long service life that can be extended indefinitely by replacement of an inexpensive component.

Other objects and advantages will become apparent from the following description of the exemplary form of invention shown in the drawings, in which:

Figure 1 is a fragmentary elevational view of a filling machine embodying the invention;

Fig. 2 is a fragmentary horizontal sectional view taken along the line 2—2 of Fig. 1;

Fig. 3 is a simplified sectional view taken along the line 3—3 of Fig. 2 but showing a different position of adjustment of the machine;

2

Fig. 4 is a schematic illustration of the machine as viewed from above; and

Fig. 5 is a fragmentary sectional view taken along the line 5—5 of Fig. 1.

5 Designed to fill measured quantities of a pulverous or particled material into a continuously moving parade or succession of upwardly open cans 10, Figs. 1 to 3, the improved filling machine forming the illustrated embodiment of the invention is quite complex in its overall construction. However, the matter of fully disclosing the invention is simplified by the fact that much of the component structure of the improved machine is of standard construction which need not be specifically illustrated and described in the present application. Reference may be made to similar filling machines of the prior art for a complete disclosure of filling machine structure not disclosed in detail in this application.

In general, the improved machine embodying the present invention comprises a circular filling head or turret 20 of conventional construction mounted for rotation about a vertical axis. The means used to support and rotatably drive the filling head 20 is similar to that used in standard machines. As shown, the filling head 20 includes an annular series of depending vertical filling or measuring tubes 14 circumferentially spaced from each other.

Completely open at its lower end, each filling tube 14 coacts at its upper end with measuring structure (not shown) of a generally conventional design, which operates to fill a pulverous or particled material into the tube during certain predetermined portions of the rotary movement of the tube in its circular path. Described here, for convenience, by the words "pulverous" or "particled" the materials filled into cans by machines of the type provided by this invention are ordinarily finely divided solids, which have to a degree some of the flow or pouring characteristics of a liquid. Structure suitable for filling such material into each tube 14 in accordance with the circumferential position of the tube around the axis of rotation of the filling head is well known to those skilled in the art.

A continuous parade or succession of upwardly open cans 10 is supplied to the machine by a suitable conveyor 16, Fig. 2, which connects with can feeding means 18 mounted on one side of the machine. The feeding means 18 includes a star wheel 20 mounted on a vertical drive shaft 22, Fig. 1, which is rotated in timed relation to the filling head 20 by suitable drive means provided for this purpose.

50 The periphery of the star wheel 20 is scalloped to pick up the successive cans 10 from the conveyor 16 and swing the cans in spaced relation to each other across a horizontal support plate 23 and along an arcuate guide 24 to a feeding station or position 26, Fig. 2, underlying the circular path of movement of the filling tubes 14. The successive cans 10 are supported in the feeding station 26 by a portion of the plate 23 which is spaced sufficiently below the lower ends of the filling tubes 14 to provide vertical clearance between the latter and the cans.

60 The timed movement of the star wheel 20 is synchronized with the rotating filling head 20 to move each can 10 into the feeding station 26 simultaneously with movement of a coacting filling tube 14 into overlying relation to the station and hence into overlying relation to the can.

65 To receive a measured quantity of material from the overlying filling tube 14, a can moved onto the feeding station 26 must be elevated from the feeding station into telescoping relation to the lower end of the tube. Since the filling head 20 including the tubes 14 rotates continuously, each can 10 must be telescoped upwardly around its coacting tube while the tube continues to move horizontally in its circular path.

In general, the portion of the circular or angular movement of each tube 14 about the axis of the filling head 12 that is consumed in elevating a coacting can 10 into telescoping relation to the tube is not fully available for measuring material through the tube into the can. Since filling of the tube must be delayed until the coacting can is adequately telescoped around the tube, the extent of the circumferential movement of the tube that is available for measuring material into the tube and coacting can is directly affected by the extent of the circumferential movement of the tube that is consumed in telescoping the coacting can into filling position.

The radial angle of the circumferential movement of each tube 14 which can be used for filling the tube determines, for any given speed of rotation of the filling head 12, the time available for filling the tube. The available time for filling each tube 14 for various operating speeds of the machine is a critical factor in determining the speed and efficiency with which the machine will fill cans with pulverous or particled materials. While such materials will "flow" to a certain degree, the time required for moving a material of this character into and through a filling or measuring tube is necessarily a limiting factor affecting the maximum operating speed of filling machines handling the material.

In the improved machine incorporating the present invention the time available for filling material into each tube 14, for any given speed of rotation of the filling head 12, is distinctly increased by sharply reducing the circumferential movement of each tube consumed in elevating a coacting can into filling position in relation to the tube, thus extending the circumferential movement of the tube through which it is filled with the pulverous or particled material.

This is accomplished by using a power driven endless flexible element or belt 30 to directly engage and lift each successive can 10 from the feeding station 26 to an elevated station or position 32 in which the can is telescoped into a filling position around the coacting tube 14. Preferably the belt 30 is of a reinforced rubber construction such as that commonly used in automobile fan belts.

A drive pulley 31 for the belt 30 is mounted beneath the plate 23 substantially in underlying relation to the feeding station 26. The pulley 31 is rotated in the counterclockwise direction (as viewed in Fig. 1) by a gear 33 which meshes with a drive gear 37 that rotates with the drive shaft 22 for the star wheel 20.

Trained over the drive pulley 31 the belt 30 has an upper run 34 which extends upwardly through a slot 36 in the plate 23 to an upper pulley 38 immediately underlying the elevated receiving station 32. As shown, the receiving station 32 is displaced horizontally from the feeding station 26 in the direction of rotation of the overlying tubes 14.

Emerging upwardly through the plate slot 36 at one edge of the feeding station 26, the upper belt run 34 has a steep angle of inclination (which can be of the order of 45° relative to a horizontal plane) to provide a high rate of lift for the cans 10 picked up at the feeding station. Thus, the horizontal displacement of the receiving station 32 from the feeding station 26 and, hence, the circumferential movement of each tube 14 between the feeding station 26 and the receiving station 32 can be reduced to a distance approximately equal to the vertical distance through which each can is raised from the feeding station 26 to reach the receiving station.

As shown in Fig. 2, the horizontal disposition of the two belt pulleys 31 and 38 is such that the upper belt run 34, as viewed from a position directly above the belt, is generally tangent to the medial portion of the arc through which the axis of each tube 14 progresses in moving between the feeding station 26 and the receiving station 32.

The upper belt pulley 38 is suitably journaled in a hori-

zontal support bushing 40, Figs. 2 and 3, fixed to a vertical bracket plate 42. The previously mentioned counterclockwise rotation of the drive pulley 31, Fig. 1 circulates or drives the belt 30 in its course in a direction such that its instantaneous upper run portion 34 moves toward the receiving station 32.

To accommodate the machine to filling either tall or short cans, provision is made for supporting the bracket plate 42 in either of two vertically spaced positions on a vertical support channel 44. As shown in Fig. 1, the bracket plate 42 is supported in its upper position by two shoulder screws 46 having convenient operating handles 48. To hold the bracket plate 42 in this position the shoulder screws 46 are threaded into the plate through an upper pair of apertures 50 in the web of the channel 44. To support the bracket plate 42 in its lower position, Fig. 3, the shoulder screws 46 are threaded into the plate through a lower pair of apertures 52 in the channel 44, Fig. 1, located directly below the upper aperture 50, respectively. Thus the horizontal position of the bracket plate 42 and attached parts remains unchanged by adjustment of the plate between its two vertical positions.

However, shifting of the bracket plate 42 from one vertical position to another changes the center distance between the upper pulley 38 and the lower pulley 31 for the belt 30. To compensate for this, the lower run 54 of the belt 30, which extends between the pulleys 38 and 31, is trained around an idler pulley 56, Fig. 3, which can be adjusted to take up slack in the belt. As shown, the idler pulley 56 is journaled on one corner of a triangular plate 58 swingably supported on the bracket plate 42 by means of a pivot pin 60 extending through the plate 58 in spaced relation to the axis of the idler pulley.

In the construction shown, the idler pulley 56 is located almost directly below the upper pulley 38 when the bracket plate 42 is mounted in its upper position, Fig. 1. Upon shifting of the bracket plate 42 to its lower position, Fig. 3, the plate 58 is swung counterclockwise to move the idler pulley 56 away from the upper belt run 34 sufficiently to take up the slack in the belt. For either position of the bracket plate 42, the plate 58 is adjusted about the pivot 60 to provide optimum tension on the belt 30 and clamped in its adjusted position by tightening a cap screw 62 extending through an arcuate slot 64 in the plate 58 into the bracket plate 42.

The matter of maintaining the cans 10 in vertical positions while moving from the feeding station 26 to the receiving station 32 is simplified by the fact that each can is lifted by energy supplied directly to the can through the power driven belt 30. Thus relieved of any necessity for applying to the individual cans the power required to lift the cans, the means used to maintain the cans in vertical positions can be designed to provide sufficient clearance around the respective cans to avoid binding or jamming of the cans against the coacting structure.

Thus upon reaching the feeding station 26, the cans 10 are maintained in general vertical alignment with the overlying tubes 14 by a plurality of vertically elongated guides 66 equal in number to the tubes. As shown in Fig. 2, the vertically elongated guides 66 extend radially outward between the successive tubes 14 from a vertical supporting cylinder 68 which rotates with the filling head 12. The cylinder 68 and the two guides 66 adjacent each tube 14 are dimensioned and shaped to partially embrace the side of the tube adjacent the cylinder while at the same time leaving unobstructed an annular space 70 around the tube for the reception of a can 10. Opposite ends of each guide 66 extend substantial distances above and below the lower ends of the tubes 14, as shown in Fig. 1.

Thus, upon being moved by the star wheel 20 into the feeding station 26, each can 10 is loosely embraced by the two vertical guides 66 adjacent the overlying filler

tube 14. The two guides 66 thus brought into coaxing relation to the can 10 cooperate with the star wheel 20 in continuing horizontal movement of the can onto the upwardly exposed surface of the upper belt run 34.

By the time each can 10 is picked up by the belt run 34, the side of the can away from the cylinder 68 is embraced by the lower ends of two cantilever guide rails 72, 74, extending downwardly in vertically spaced, generally parallel relation to the upper belt run 34 from a support bracket 76. The bracket 76 is secured to the vertical channel 44 by cap screws 78, 80 that provide for vertical adjustment of the bracket and the attached guide rails 72, 74.

As previously intimated, the vertical guides 66 and the guide rails 72, 74, which maintain each can 10 in a vertical position as it is elevated by the upper belt run 34, are shaped and dimensioned to provide sufficient radial clearance around the can to minimize the incidence of fouling of cans in the machine even though some cans may be marred by substantial defects.

Upon being lifted by the belt run 34 to the receiving station 32, each can 10 is supported on one end of an auxiliary can support rail or cam 82, Figs. 2 and 3. The opposite end of the auxiliary can support 82 is welded to the projecting end of a cantilever 84 attached to a vertical hinge plate 86. The hinge plate 86 is supported on the bracket plate 42 by a hinge 88, Figs. 1 and 2. The hinge 88 provides for horizontal swinging movement of the hinge plate 86 from a normal position coplanar with the bracket plate 42 (in which position the auxiliary can support 82 is positioned as shown in Fig. 2 to support a can 10 at the receiving station 32) and servicing positions in which the hinge plate 86 is swung away from the cylinder 68 to move the auxiliary can support 82 horizontally out from under the filling tubes 14.

As shown, the hinge plate 86 is releasably held in its normal position by a vertically swingable clamp 90, Fig. 1, extending over the lower edge of the hinge plate 40 from a thumbscrew 92 in the bracket plate 42.

A socket 94 and thumbscrew 96, Figs. 2 and 3, on the upper medial portion of the hinge-supported cantilever 84, adjustably support an auxiliary can guide rail 98, which provides continuing lateral support to the cans moving upwardly beyond the main guide rails 72, 74 to the receiving station 32.

From the receiving station 32 each can is carried along horizontally by its coaxing filling tube 14 and the adjacent guides 66. Thus the can is moved horizontally from the auxiliary can support rail 82 onto a main can support rail or cam 100. Having a generally arcuate shape as viewed from above, Fig. 2, the main can support rail 100 is supported in underlying relation to the adjacent filling tubes 14 by suitable support standards 102, Figs. 1 and 3. The supports 102 can be adjusted vertically to effect a vertical alignment between the main can support rail 100 and the auxiliary can support 82 mounted on the vertically adjustable bracket plate 42.

Because of the inherently efficient lifting action of the belt 30 and the generous radial clearances provided between each can and the guide structure which maintains the can in a vertical position while moving into telescoping relation to its coaxing filling tube 14, fouling of a can in the can lifting and guide structure is extremely unlikely even though the can may be marred by defects such as would cause jamming in conventional machines.

Although it is extremely unlikely that a can 10 fed to the machine will fail to telescope properly around a coaxing filling tube 14, highly efficient means is provided for immediately detecting any abnormal resistance to movement of a can into telescoping relation to its feeding tube and automatically stopping the filling machine before the can has an opportunity to cause a troublesome jam in the machine. Moreover, a faulty can 10

causing the machine to stop automatically can be quickly replaced with a good can to minimize the interruption in the normal operation of the machine.

To sense any abnormal pressure on the upper belt run 34, such as might be caused by abnormal resistance to telescoping of a can upwardly around its coaxing filling tube 14, a straight elongated belt support bar 104 is yieldably supported in immediate underlying relation to the upper belt run 34. The lower end of the support 104 pivots about a stationary pivot 106 adjacent the driving pulley 31. The upper end of the belt support 104 rests on a cantilever bracket 108 extending laterally from the bracket plate 42.

Actually, the support 104 is yieldably urged toward the belt run 34 by a compression spring 110, Figs. 1, 3 and 5, interposed between the upper face of the bracket 108 and the lower side of the belt support. As shown, the spring 110 encircles a retaining bolt 112 threaded into the belt support 104 and extending down through a slot 114, Fig. 5, formed in the bracket support 108. A head 116 on the lower end of the bolt 112, Fig. 1, engages the underside of the bracket 108 to limit upward movement of the belt support 104 by the spring 110.

Downward movement of the belt support 104 is limited to a small angle by engagement with the upper face of the bracket 108 of the lower end of a stop bolt 118, Figs. 1, 3 and 5, extending downwardly from a lateral bracket 120 fixed to the belt support 104.

Abnormal depression of the belt support 104 by excessive can pressure on the belt run 34 is used to operate a limit switch 122—suitably connected electrically to interrupt operation of the filling machine. As shown in Figs. 1, 3 and 5, the switch 122 is supported on the underside of the bracket 108. An upwardly exposed operating plunger 124 on the switch 122 is engaged by either of two adjustable switch actuating screws 126 or 128, depending upon the vertical position of the assembly mounted on the bracket plate 42. Both screws 126, 128 are adjustably mounted in vertically spaced relation to each other on the bracket 120 attached to the left support 104.

The positional relationship of the two switch actuating screws 126, 128 to the belt support 104 is such that when the bracket plate 42 is in its upper position, Figure 1, the screw 126 is automatically aligned operatively with the switch operating plunger 124.

Shifting of the bracket plate 42 from its upper position, Figure 1, to its lower position carries the upper belt pulley 38 and the cantilever bracket 108 vertically downward. At the same time the angle of inclination of the upper belt run 34 and the belt support 104 is decreased. The concurrent vertical displacement of the switch 122 and angular displacement of the belt support 104 incident to vertical adjustment of the bracket plate 42 brings the switch actuator 128 into coaxing alignment with the switch plunger 124, as shown in Figure 3.

At the same time the retaining bolt 112 moves to the end of the slot 114 remote from the pivot 106. As shown in Figs. 1 and 5, the portion 130 of the bracket 108 defining this end of the slot 114 is offset upwardly to coax with the bolt 112 to define a correct upper position for the belt support 104, when the bracket plate 42 is in its lower position. Similarly, an upward offset abutment 132, Figs. 1 and 5, is provided on the bracket 108 to coax with the stop bolt 118 to properly limit depression of the belt support 104 when the bracket plate 42 is in its lower position.

Thus, the stop switch 122 and the belt support 104 are automatically conditioned for proper operation upon movement of the bracket 42 to either of its two vertical positions. Hence, adjustment of the machine to elevate either tall or short cans into filling position requires merely a change in the vertical adjustment of the bracket plate 42 together with vertical adjustment of the main

can support rail 100 and possibly an adjustment of the bracket 76 supporting the guide rails 72 and 74.

In the event of abnormal can pressure of the belt run 34 the switch 122 operates to stop the machine before the faulty can reaches the main can support rail 100. This provides an opportunity for replacing the faulty can with a new can. As previously explained, the auxiliary can support 82 can be quickly moved to an out-of-the-way position to permit lowering of the lifter mechanism. Other parts of the can lifting mechanism supported on the bracket plate 42 can be easily moved to permit replacement of a fouled can which has not reached the receiving station 32.

Further, in regard to the efficiency of the improved machine, it will be appreciated with reference to the diagrammatic illustration of the machine in Fig. 4 that the radial angle of the zone of circumferential movement 136 of each tube 14 consumed in elevating a can from the feeding station 26 to the receiving station 32 is sharply minimized to extend the radial angle of the zone 138 of circumferential movement of each tube 14 that is available for filling material into the tube.

The next succeeding zone 140 of the circumferential movement of each tube 14 is used in a conventional manner to complete discharging of material through the tube into the coacting can. At the end of the discharge zone 140 each can is directed away from the machine by a conventional outlet star wheel 142. After passing the star wheel 142 each tube 14 moves on to the feeding station 26 where it comes into horizontal alignment with another can moved onto the feeding station 26 in the manner described.

Since the horizontal position of the receiving station 32 is unchanged by adjustment of the bracket plate 42 to accommodate the machine to filling cans of different height, the extended radial angle of the tube filling zone 138 provides for filling either tall or short cans with substantially equal efficiency.

Because of the substantial extension made in the radial angle of the tube filling zone 138, the improved machine provides at once for filling cans at an increased numerical rate, filling larger and taller cans, and measuring the material into each can with increased accuracy.

The more efficient machine thus provided is inherently capable of operating effectively over an extremely long service life. Since there is substantially no sliding movement between each successive can 10 and belt 30, the belt is not subject to substantial wear in use. Moreover, the belt 30 can be readily replaced if necessary.

While I have shown and described a preferred embodiment of my invention it will be apparent that variations and modifications thereof may be made without departing from the principles and scope of the invention, I therefore desire, by the following claims, to include all such variations and modifications by which substantially the results of my invention may be obtained through the use of substantially the same or equivalent means.

I claim:

1. In a machine for filling a continuously moving succession of upwardly open containers with finely divided material, the combination of an annular assembly of downwardly open vertical filling tubes mounted for rotation continuously about a vertical axis to move the tubes through a common circular path, an endless belt, means supporting said belt so that the latter has a container elevating run steeply inclined relative to a horizontal plane and disposed in generally underlying relation to a segment of said circular path of movement of said filling tubes, the upper end of said container elevating belt run substantially underlying said filling tube movement path at a container filling level relative to the overlying filling tubes, said means supporting said belt including a rotary drive pulley engaging the belt to circulate the latter in a direction which carries the instantaneous lower end of said elevating run toward said

upper end of the run, container support means extending from the upper end of said belt run in the direction of rotation of the overlying filling tubes, and container feeder means positioned to feed containers onto the lower end of said belt run below the lower ends of overlying filling tubes.

2. In a machine for filling a continuously moving succession of upwardly open containers with particled material, the combination of a filling head rotatable about a vertical axis and including a circular series of depending vertical filling tubes movable through a circular path upon rotation of the filling head, means defining a container feeding station underlying the circular path of movement of said tubes to support a container below the lower ends of said tubes, container feeding means positioned to feed a succession of upwardly open containers onto said feeding station, container supporting means defining a container receiving station displaced a short distance horizontally from said feeding station in the direction of rotary movement of the overlying filling tubes and underlying the circular movement path of said filling tubes, said receiving station being spaced vertically above said feeding station to support containers in telescoped relation to the overlying filling tubes, an endless container elevating belt, means supporting said belt to form an upwardly exposed belt run steeply inclined upwardly from said feeding station to said receiving station, said belt supporting means including drive means coacting with the belt to drive the belt in a direction which moves the instantaneous run portion thereof upwardly from said feeding station to said receiving station, and container guide means disposed in adjacent relation to said belt run.

3. In a machine for filling finely divided material into a continuously moving succession of upwardly open containers, the combination of an annular assembly of open vertical filling tubes, said assembly being rotatable about a vertical axis to move the tubes through a circular path, an endless belt, means supporting said belt to form an upwardly exposed container elevating run underlying a segment of said circular filling tube path and steeply inclined upwardly in the direction of rotary movement of the overlying tubes, said belt supporting means including means for driving said belt in a direction to move the instantaneous run portion thereof upwardly, the upper end of said belt underlying said tube movement path at a container filling level, elevated container support means extending from the upper end of said belt run in the direction of rotary movement of the overlying tubes, container feeding means mounted to feed containers to the lower end of said belt run in underlying relation to said tube movement path, a movable switch-control element yieldably supported in immediate underlying relation to said belt run for actuation by excessive depression of the latter, a safety switch mounted for operation by said switch control element and adapted to interrupt operation of the machine, and container guide means positioned adjacent said belt run.

4. In a machine for filling finely divided material into a continuously moving succession of upwardly open containers, the combination of an annular assembly of downwardly open vertical filling tubes, said assembly being rotatable about a vertical axis to move the tubes through a circular path, belt support means including an upper belt support underlying said tube movement path, an endless belt trained over said upper belt support, vertically adjustable support means coacting with said upper belt support to support the latter in different container filling levels vertically spaced from each other, said belt support means including a lower belt support located at a container feeding level substantially below said container filling levels, said belt being trained around said lower belt support to define a container elevating belt run extending between said upper and lower belt supports, said lower belt support being positioned horizontally to locate said belt run below a segment of said

circular tube movement path, said lower belt support having a horizontal spacing from said upper belt support which is so related to the various vertical spacings between said upper and lower belt supports that said belt run is steeply inclined upwardly in the direction of rotary movement of the adjacent tubes, said belt support means including adjustable means engageable with said belt to assure proper tension therein for the various positions of vertical adjustment of said upper belt support, said belt support means including means operative to drive said belt to move the instantaneous run portion thereof upwardly from said lower to said upper belt support, vertically adjustable container support means underlying said tube path from the upper end of said belt run and extending in the direction of rotation of the overlying tubes, and container feeding means positioned to feed containers onto the lower end of said belt run.

5. In a machine for filling a finely divided material into a continuously moving succession of upwardly open containers, the combination of a filling head rotatable about a vertical axis and including an annular series of open vertical filling tubes movable through a circular path upon rotation of the head, means defining a container feeding station underlying said filling tube path, container feeding means mounted to feed a succession of upwardly open containers to said feeding station, an endless belt, belt support and driving means supporting said belt to define a container elevating belt run steeply inclined upwardly in the direction of rotation of the overlying tubes from said feeding station to an upper end rising to a container filling level, container guide means including vertical guides rotatable with said filling head in radially spaced relation to the lower ends of said respective tubes to pass along one side of said belt run in container guiding relation to the respective tubes, said container guide means including a container guide mounted along the side of said belt run opposite said vertical guides, said container guide means on opposite sides of said belt run being shaped and dimensioned to provide loose lateral support to containers on said belt run, and container support means extending horizontally from the upper end of said belt run in the direction of rotation of the overlying tubes.

6. In a machine for filling finely divided material into a continuously moving succession of upwardly open containers, the combination of an annular assembly of downwardly open vertical filling tubes, said assembly being rotatable about a vertical axis to move the tubes through a circular path, an endless belt, means supporting said belt to form an upwardly exposed container elevating run underlying a segment of said circular filling tube path and steeply inclined upwardly in the direction of rotary movement of the overlying tubes, said belt supporting means including means for driving said belt in a direction to move the instantaneous run portion thereof upwardly, the upper end of said belt underlying said tube movement path at a container filling level, container support means extending horizontally from the upper end of said belt run in the direction of rotary movement of the overlying tubes, container feeding means mounted to feed containers to the lower end of said belt run in underlying relation to said tube movement path, a movable switch-control element yieldably supported in immediate underlying relation to said belt run for actuation by excessive depression of the latter, a safety switch mounted for operation by said switch control element and adapted to interrupt operation of the machine, and container guide means positioned adjacent said belt run.

7. In a machine for filling a finely divided material into a continuously moving succession of upwardly open containers, the combination of a filling head rotatable about a vertical axis and including an annular series of downwardly open vertical filling tubes movable through a circular path upon rotation of said head, means defining a container feeding station underlying said filling tube

path, container feeding means mounted to feed a succession of upwardly open containers to said feeding station, an endless belt, belt supporting means supporting said belt to define a container elevating belt run steeply inclined upwardly in the direction of rotation of the overlying tubes from said feeding station to an upper end underlying said tube path at container filling level, said belt supporting means including means for driving said belt in a direction to move the instantaneous run portion thereof upwardly, said belt supporting means including an upper belt support supporting said belt at the upper end of said run thereof, vertically adjustable support means coacting with said upper belt support to support the latter and the upper end of said belt run at different vertically spaced container filling levels, and vertically adjustable container supporting means underlying said circular tube path and extending from the upper end of said belt run in the direction of rotation of the overlying tubes.

8. In a machine adapted to fill finely divided material into a continuously moving succession of upwardly open containers and including an annular assembly of vertical filling tubes rotatable about a vertical axis to move the tubes through a circular path, arcuate container supporting means mounted at a container filling level in underlying relation to said circular tube path, and container feeding means positioned to define a container feeding station below said circular tube path and including means for feeding a succession of containers to the feeding station, means for increasing the filling efficiency of the machine comprising an endless belt, means supporting said belt to define a container lifting belt run steeply inclined upwardly from the feeding station to the container supporting means in the direction of rotation of the overlying tubes, and said belt supporting means including means for driving said belt in a direction to move the instantaneous run portion thereof upwardly.

9. In a machine for filling finely divided material into a moving succession of upwardly open containers, the combination of an annular assembly of downwardly open vertical filling tubes, means supporting said assembly for rotation about a vertical axis to move the tubes through a circular path, an endless flexible element, means supporting said endless flexible element so that the latter has a generally straight container elevating run underlying a segment of said circular filling tube path and steeply inclined upwardly in the direction of rotary movement of the overlying tubes, said container elevating run of said endless flexible element having an upper end underlying said tube movement path at a container filling level, said endless element supporting means including driving means coacting with said element to circulate the latter through said inclined run toward said upper end thereof, container support means extending from said upper end of said endless flexible element in the direction of rotary movement of the overlying tubes, container feeding means mounted to feed containers onto said upwardly inclined run of said endless flexible element at a feeding level lower than said upper end of the run, and container guide means disposed in proximate relation to said inclined run of said flexible element.

10. In a machine for filling finely divided material into a moving succession of upwardly open containers, the combination of an annular assembly of downwardly open vertical filling tubes, said assembly being rotatable about a vertical axis to move the tubes through a circular path, a movable container elevating element supported below said filling tubes and defining an upwardly exposed movable surface extending continuously in a generally straight line underlying a segment of said circular filling tube path and steeply inclined upwardly in the direction of rotary movement of the overlying tubes, said exposed movable surface of said container elevating element having an upper end underlying said tube movement path at a container filling level, operating

11

means connected to said container elevating element to drive the latter in a direction which causes the instantaneous upwardly exposed surface thereof to move toward the said upper end thereof along said inclined line of the surface, container support means extending from said upper end of said inclined elevating element surface in the direction of rotary movement of the overlying tubes, and container feeding means mounted to feed containers onto the lower end of said inclined surface of said container elevating element in underlying relation to said tube movement path.

11. In a machine for filling a continuously moving succession of upwardly open containers with finely divided material, the combination of a filling head rotatable about a vertical axis and including an annular series of depending vertical filling tubes movable through a circular path upon rotation of the filling head, means defining a container feeding station underlying said circular tube movement path to support a container below the lower ends of said tubes, container feeder means positioned to feed a succession of upwardly open containers onto said feeding station, container supporting means defining a container receiving station displaced a short distance horizontally from said feeding station in the direction of rotary movement of the overlying tubes and underlying the circular movement path of said tubes, said receiving station being located upwardly from said feeding station to support containers in telescoped relation to the overlying filling tubes, an endless flexible container elevating element, means supporting said endless flexible element so that the latter has a substantially

12

straight upwardly exposed run steeply inclined upwardly from said feeding station to said receiving station, and said endless flexible element supporting means including drive means coacting with said element to circulate the element upwardly through said inclined run to lift containers from said feeding station to said receiving station.

5 12. In a machine for filling finely divided material into a succession of upwardly open containers, the combination of an annular assembly of downwardly open vertical filling tubes, said assembly being rotatable about a vertical axis to move the tubes through a circular path, means defining a container receiving station underlying said tube movement path at a predetermined level at which said receiving station defining means is capable 15 of supporting a container in telescoping relation to an overlying filling tube, container support means extending from said receiving station in the direction of rotary movement of the overlying tubes, an endless flexible container elevating element, means supporting said endless flexible element to have a substantially straight run underlying a segment of said filling tube path and steeply inclined downwardly in a direction opposite to the direction of rotary movement of the overlying tubes, said substantially straight run of said endless element having 20 an upper end extending to said receiving station, said endless element support means including drive means coacting with the element to circulate the element upwardly through said run, and container feeding means mounted to feed containers onto said inclined endless element run at a feeding level lower than said receiving station.
